UNITED STATES PATENT OFFICE

2,054,594

ELECTRICAL HEATING APPARATUS

Arthur G. Borden, Washington, D. C., assignor,
by mesne assignments, to The Borden Industries, Inc., a corporation of Delaware

Application March 20, 1931, Serial No. 524,142
Renewed November 20, 1935

8 Claims. (Cl. 219—24)

My invention relates broadly to electrical heating apparatus and more particularly to a simplified construction of tubular type electric heater.

One of the objects of my invention is to provide a construction of electrical heating apparatus of tubular form into which any object which is to be subjected to heat may be inserted and the heat concentrated therein while maintaining the exterior of the surrounding casing relatively cool.

Another object of my invention is to provide an improved form of electric heater for hair waving apparatus having means for concentrating the heat within a central chamber for subjecting the hair on the curling mandrel to heat treatment while maintaining the exterior of the heater relatively cool.

Still another object of my invention is to provide a simplified construction of electric heater for hair wavers, the parts of which are capable of quantity production at low cost and which may be readily assembled for forming a complete electric hair waving apparatus.

A further object of my invention is to provide an arrangement for mounting a heating element within a multiple section shell of a heater chamber having means for preventing heat conduction or radiation outside of the shell while concentrating the heat within the heater chamber without in the shell.

A still further object of my invention is to provide a construction of electric heater for hair waving apparatus employing a two-part shell casing wherein the heating element is carried by a tubular support which may be centered between end members within the casing, heat radiation from the electric heater being concentrated centrally toward the inner chamber while conduction and radiation losses exterior of the casing are substantially nil.

Another object of my invention resides in an arrangement of a terminal connector for an insertable heating coil for the chamber of a hair waver whereby the heating coil may be renewed from time to time as may be required.

Still another object of my invention is to provide a construction of closure for the end of the heater chamber whereby the heater chamber may be readily inserted over the mandrel which carries the hair in coiled arrangement for subjecting the hair to heat treatment.

Other and further objects of my invention reside in the construction of electrical heater as set forth more fully in the specification herein-

after following by reference to the accompanying drawings, in which:

Figure 1 is a side elevation showing the heater of my invention; Fig. 2 is a side elevation of the heater chamber taken in a position revolved 90° from the view shown in Fig. 1; Fig. 3 is a longitudinal cross-sectional view taken through the heater chamber shown in Figs. 1 and 2 with the shell for the heater coil shown in side elevation; Fig. 4 is a longitudinal cross-sectional view taken through the heater chamber and heating coil in the hair waver construction of my invention; Fig. 5 is a lateral cross-sectional view taken on line 5—5 of Fig. 3; Fig. 6 is a fragmentary cross-sectional view taken through one of the terminal members in the construction illustrated in Fig. 4; Figure 7 is a perspective view of the heater system; and Figs. 8 to 11 are perspective views of the various parts of the heater system.

Referring to the drawings in detail, reference characters 1 and 2 designate complementary portions of an enclosing shell for the hair waver apparatus of my invention. The complementary portions 1 and 2 are molded from heat resisting material, the portion 1 being externally screw threaded as represented at 3 and the portion 2 being internally screw threaded as represented at 4 for providing a rigid joint intermediate the ends of the heat treatment chamber. The lower extremity of the portion 2 of the shell is formed with an annular flange 5 integrally connected with the shell 2 with an intermediate annular recessed portion 6 therebetween. A closure cap 7 is provided for the end 5 of the heat treatment chamber, the closure cap carrying a diametrically extending device therein having spring fingers 8 which are adapted to resiliently clamp over the end 5 of the heat treatment chamber and project into the annular recess 6 in the end of the shell portion 2. A gasket 21 is provided for sealing the end of the heat treatment chamber. The exterior portion of the cap 7 is provided with a series of plate members 9, 10 and 11, the plate members 10 and 11 being spaced from each other as represented at 14 to permit circulation of cooling air therebetween and reducing the conduction of heat to the surface adjacent the pad 12 which is carried by the plate 11. The pad 12 and the series of superimposed plates 9, 10 and 11, together with the cap 7, the spring device 8 therein, and the gasket 21 are suitably apertured for the passage of the strands of hair at 17 into the heat treatment chamber where the hair is wrapped upon the mandrel 19. The mandrel 19 is secured to the plates 9 and 10 by securing means 55

represented at 16. The hair which is curled upon the mandrel 19 by means of the winder 20 is maintained in position by means of the wrapper 18 during the heat treatment process. The details of the winder are more fully set forth in my Reissue Patent No. 17,832, dated October 21, 1930.

The upper end of the heat treatment chamber is partially closed by means of a cap 23 screw 10 threaded into the upper portion 1 of the shell as represented at 25. The internal bore of the cap 23 is formed to correspond with the internal bore of the portion 24 of the upper shell 1. The cap 23 is apertured at 23a for the passage of the mandrel 19 therethrough and for the escape of steam. It will be observed that the walls of the shells 1 and 2 bulge outwardly having a larger internal diameter at the center of the casing than at opposite ends of the casing. Shoulders 20 are provided at opposite ends of the casing as shown at 1a and 2a between which the elements of the heater system are mounted. The heater system includes a tubular member 34 which is disposed between two annular end members 35 and 36. The end members 35 and 36 are recessed as represented at 35a and 36a to receive the ends of the tubular member 34. The inside surface of the tubular member extends flush with the interior surface of the ring members 35 and 36. 30 The tubular member 34 provides a mounting means for the heater winding represented at 38. The heater winding 38 may be formed from any desired construction of wire such as a nichrome wire wrapped spirally upon an asbestos base. 35 The winding may be disposed in a multiplicity of layers insulated one from another, the layers extending to a predetermined distance from the opposite ends of the tubular member 34 allowing the ring members 35 and 36 to be fitted over the 40 ends of the tubular member 34.

The ends of the heater winding 38 project longitudinally from the heater element terminating as shown at 33 and arranged to enter connectors 45 27 provided in the molded heater casing as shown more fully in Fig. 4. The terminals 27 have the form of tubular members molded vertically within the molded portions 28 and 29 of the shell 1 into which the ends of the heater wire at 33 extend and into which the ends of the take-off conductors 31 extend. The heater winding is of 50 fine structure and in order to strengthen the terminals of the wire the ends are inserted into pliable metallic tubes shown at 33 which project vertically from the heater winding and enter the 55 metallic connectors 27. The pliable metallic tube or sleeve is collapsed on the end of the heater winding to insure good electrical contact. The insulated tubes 33 are held in place by the wrapping which secures the turns of the heater wire 60 on the tubular member 34. The ends of the take-off conductors 31 and the terminals to the heater wires 31 and 33 are clamped by means of screw device 32 as shown more clearly in Fig. 6 for effecting a good electrical connection. The 65 heater system has the heater member covered by a metallic heat conducting shell 40. The shell 40 has apertures cut in diametrically opposed positions 40a and 40b in opposite ends thereof as shown more clearly in Fig. 8 which 70 slots are centered over the projections 35b and 36b which are formed on the ring members 35 and 36. It will be observed that the projections 35b and 36b are each provided with a semi-circular recess for the passage of the conductors 75 33 extending from the heater winding 38 to the

terminals 27. The shell 40 is formed of thin metal with the inner surface thereof highly polished and disposed adjacent to the heater winding and leaving an air space between the polished metal surface and the heater winding. The polished 5 interior surface of the tube 40 serves to reflect heat radiated from the heater winding 38 and confine the heat to the heat treatment chamber. The polished surface on the interior of the tube 40 serves as a heat reflector retarding the penetration of heat rays through the walls of the shell portions 1 and 2.

It will be observed that the ring members 35 and 36 are formed in heat resisting material and serve to space the heater element away from the 15 portions 1 and 2 of the shell of the hair waving apparatus. The heat resisting qualities of the ring members 35 and 36 prevent conduction of heat from the heater winding 38 to the exterior shell portions 1 and 2. The air space which is 20 provided between the heater windings 38 and the interior polished surface of the tube 40 serves to permit the radiation of heat from the winding 38 toward the interior polished surface of the tube 40 from which it is reflected toward the 25 interior of the heater chamber. The properties of the metallic cylinder 40 are such that a uniform heat distribution may be maintained 30 throughout the heater chamber in that the cylinder 40 is raised to a predetermined temperature throughout the surface thereof. The exterior surface of the cylinder 40 is spaced from the interior walls of the shell portions 1 and 2 of the outer casing. Suitable apertures 1a and 2a 35 are provided to insure the dissipation of heat from within the space between the outer surface of the cylinder 40 and the interior of the shell portions 1 and 2.

As will be seen from the drawings, the assembly of the parts of the hair waving apparatus 40 is very simple in that the two parts of the shell of the outer casing are screwed together over the heater element, thereby centering the heater element within the casing and forming the heat treatment chamber for the hair waver apparatus. The conductors which establish the circuit to the heater winding 38 enter the tube of the casing and are secured by means of block 30 enabling the heater to be suspended from the conductors 3 or from an auxiliary supporting 50 cord attached to the block 30. The mandrel is maintained in position within the heater chamber by means of the spring members 8 which engage the lower portion of the heater chamber as shown.

All parts of the casing and the centering ring members 35 and 36 are readily molded and assembled in the manner shown. The heater system which is centered within the casing may be readily removed for renewal or repair and provides an inexpensive assembly. The fact that the inner surface of the shell 40 serves as a heat reflector insures that the shell portions 1 and 2 are maintained relatively cool under conditions of operation of the heater thereby permitting the operator to conveniently adjust the position of each of the hair wavers in a group of hair wavers without danger to the operator or the patron.

While I have shown my invention as applying particularly to a hair waving apparatus, I desire that it be understood that my invention has many applications, such as a heater for medicinal purposes and therapeutical purposes. I have found the construction of heater of my invention suitable for vaporizers where it is de- 75

sired to produce a vapor from a solution carried by an absorber within the heater chamber.

I have found the construction of heater of my invention suitable for vaporizers where it is desired to produce a vapor from a solution carried by an absorber within the heater chamber for medicinal purposes and therapeutical uses.

I have found the construction of hair waving apparatus described herein highly practical, and 10 while I have described one embodiment of my invention I desire that it be understood that modifications may be made and that no limitations upon my invention are intended other than are imposed by the scope of the appended claims.

15 What I claim as new and desire to secure by Letters Patent of the United States is as follows:

1. Hair waving apparatus comprising a heat resisting casing, a heater unit disposed within said casing, said unit including a cylindrical member, an annular member of heat resisting material carried by each end of said cylindrical member and operating to space said cylindrical member from the material of said casing, a heater winding carried by said cylindrical member, a cylindrical shield disposed between the annular members on the ends of said cylindrical member and interlocked with said annular members, said cylindrical shield having a high degree of heat conductivity for uniformly distributing heat throughout the length of said cylindrical member, a heat reflecting surface formed on the interior of said cylindrical shield for concentrating heat from said heater winding interiorly of said cylindrical member and means projectible axially through said cylindrical member for supporting hair in wound formation therein for waving the hair.

2. Hair waving apparatus comprising a casing of heat resisting material, terminals formed in 40 said casing, a removable heater unit having connectors extending therefrom for establishing electrical connection with the terminals in said casing, said heater unit comprising a pair of concentrically disposed tubular members, a 45 winding disposed therebetween and terminating in said connectors, spacer blocks of heat resisting material positively spacing said tubular members from each other and from the interior walls of said casing and means projectible axially 50 through said cylindrical member for supporting hair in wound formation therein for waving the hair.

3. An electrical heating device comprising a casing composed of a pair of substantially cylindrical half-sections threadedly connected together at their adjacent ends and each provided with an internal shoulder means, and a unitary electrical heating element entirely separate and distinct from said casing disposed within the latter, said heating element comprising a tube, an electrical resistance element wound thereon, and a ring at each end of said tube engaging the side wall of the related casing section to maintain the heating element between said rings spaced from the casing and also engaging said shoulder means, respectively, whereby threading together of the casing sections clamps the heating element within the casing.

4. An electrical heating device comprising a 70 casing composed of a pair of substantially cylind-

rical half-sections threadedly connected together at their adjacent ends, a unitary electrical heating element entirely separate and distinct from said casing disposed within the latter, means whereby threading together of said casing sections clamps said heating element within the casing, and means whereby said heating element when clamped within the casing is maintained coaxial therewith and in spaced relationship to the side walls of the casing sections, the said side walls of the casing sections having openings for the circulation of air into and through the casing about said heating element.

5. An electrical heating device comprising a casing composed of a pair of substantially cylindrical half-sections threadedly connected together at their adjacent ends and each provided with internal shoulder means, an electrical heating element entirely separate and distinct from said casing disposed within the latter, said heating element comprising a tube, an electrical resistance element wound on said tube, a ring at each end of the tube projecting laterally beyond the tube and engaging the side wall of the related casing section to hold the heating element coaxial with the casing, said rings further engaging said shoulder means, respectively, whereby threading together of the casing sections clamps the heating element within the casing, one of said rings having grooves to accommodate terminal portions of the resistance winding, a sleeve enclosing the resistance winding, and interfitting formations between the ends of said tube and said rings holding the rings and tube against rotation relative to each other.

6. An electrical heating device of the class described comprising in combination with a two-part casing, a unitary electrical heating element entirely separate and distinct from said casing and removably clamped therein, said heating element comprising an inner tube, an electrical resistance element wound on said inner tube, a spacing ring element fitted to each end of said tube and seated against the casing, and an outer metal tube telescoped over the resistance element and having an interlocking engagement with both ring members.

7. An electrical heating device of the class described, comprising in combination, a hollow casing having air ventilating holes in its wall, a unitary electrical heating element separate and distinct from the casing and removably clamped therein in spaced relation from the casing wall, said heating element comprising an inner tube, an electrical resistance element wound onto said inner tube, and an outer heat reflector metal tube telescoped over the resistance element.

8. An electrical heating device of the class described, comprising in combination, a hollow casing having air ventilating holes in its wall, a unitary electrical heating element separate and distinct from the casing and removably clamped therein in spaced relation from the casing wall, said heating element comprising an inner tube forming an interior heating chamber, an electrical resistance element wound onto said inner tube, and an outer heat reflector metal tube telescoped over the resistance element.
